* cited by examiner

Primary Examiner—Freda S. Nunn*Assistant Examiner*—Kevin K Rudzinski(74) *Attorney, Agent, or Firm*—Howard & Howard Attorneys, P.C.(57) **CLAIM**

The ornamental design for a light guard, as shown and described.

DESCRIPTION

FIG. 1 is a front elevation view of the light guard,

FIG. 2 is a top perspective view of the light guard; and,

FIG. 3 is a bottom perspective view of the light guard.

The phantom lines are environmental only and form no part of the claimed design.
